UNITED STATES PATENT OFFICE.

ANDREW J. BARR, OF MANSFIELD, OHIO, ASSIGNOR OF ONE-HALF TO HERMAN E. HOMBERGER, OF MANSFIELD, OHIO.

DESIGN FOR A COMBINED FIXTURE AND VALVE.

50,866.

Specification for Design.

Patented June 5, 1917.

Application filed July 31, 1916. Serial No. 112,473. Term of patent 3½ years.

To all whom it may concern:

Be it known that I, ANDREW J. BARR, residing at Mansfield, in the county of Richland and State of Ohio, a citizen of the United States of America, have invented a new, original, and ornamental Design for a Combined Fixture and Valves, of which the following is a specification, reference being had to the accompanying drawing, forming a part thereof.

Figure 1 is a front elevation of a combined fixture and valves showing my new design.

Fig. 2 is a side elevation of a combined fixture and valves showing my new design.

I claim:

The ornamental design for a combined fixture and valve as shown.

ANDREW J. BARR.

In the presence of—

JOHN H. COSS,
GLADYS L. LEINARD.
